UNITED STATES PATENT OFFICE

2,291,885

CATALYTIC CONVERSION OF HYDRO-CARBONS

Gustav Egloff, Chicago, Ill., assignor to Universal Oil Products Company, Chicago, Ill., a corporation of Delaware

Application August 21, 1940, Serial No. 353,517

5 Claims. (Cl. 196—53)

This invention relates to a process for converting hydrocarbon oil into substantial yields of high anti-knock gasoline. More particularly it relates to a combination catalytic cracking and reforming process wherein gasoline of desirable properties is produced from hydrocarbon distillates containing substantial quantities of sulfur compounds. Such distillates may be from any suitable hydrocarbon source but are normally of petroleum origin and of a boiling range comprising gasoline or naphtha as well as higher boiling fractions, for example, including kerosene, gas oil and wax distillate cuts.

In one specific embodiment the present invention comprises a process consisting of treating a hydrocarbon oil with a hydrogen-containing gas in the presence of a powdered desulfurizing catalyst, separating the reaction products into gas, gasoline and a distillate fraction, removing the hydrogen sulfide from the gas as hereinafter indicated, subjecting the gasoline to a catalytic reforming step in the presence of powdered catalyst, subjecting the distillate fraction of charging stock to catalytic cracking in the presence of a powdered catalyst, recovering gasoline and gas, combining the gas with the gas from the aforesaid desulfurizing step, removing sulfur therefrom, supplying a portion of hydrogen-containing gas to the said desulfurizing step and returning a portion of the higher boiling oil from the catalytic cracking step to the desulfurizing step.

The process is further understood by reference to the accompanying drawing which is diagrammatic and should not be construed as limiting it to the exact apparatus shown therein.

The charging stock for the process is introduced through line 1, valve 2 and pump 3 to coil 4 which is disposed in heater 5. A powdered desulfurizing catalyst is introduced from catalyst charger 6 through line 7, valve 8, pump 9 and valve 10. This catalyst may comprise any suitable agent such as for example a metal sulfide including nickel sulfide, molybdenum sulfide and the like, or any other suitable catalytic material which promotes desulfurization without being substantially poisoned by the hydrogen sulfide generated in the process. The reaction mixture may be heated to a temperature within the range of approximately 300—800° F. and preferably 300—600° F. at a pressure of approximately 100—1000 pounds per square inch or higher in coil 4. The mixture then passes through line 11 and valve 12 to reactor 13 wherein further desulfurization occurs. The reaction products pass through line 14 and valve 15 to fractionator

16. A portion of the catalytic agent and higher boiling oil may be withdrawn from the fractionator through line 17 and valve 18 while another portion may be recycled to the dehydrogenation step through line 19 containing valve 20 and pump 21, joining with line 1. Gas is removed through line 22, valve 23, pump 24, valve 25 and line 26 to separation step 27 which is illustrated diagrammatically and wherein the process gases are subjected to desulfurization wherein hydrogen sulfide is removed substantially completely. This step may consist of a series of separating and treating vessels wherein the desulfurization and separation of a portion of the hydrocarbon gases, particularly the C₃ and C₄ fraction of hydrocarbons may be removed and recovered for further catalytic treatment to produce gasoline. The removal of hydrogen sulfide may be accomplished by any well-known method, such as treatment with alkali metal hydroxides or carbonates, or by treatment with tripotassium phosphate or alkyl hydroxylamines and the like. A portion of the hydrogen-containing gas is passed from desulfurizing step 27 through line 28, valve 29, pump 30, line 31, valve 32, line 33 and valve 34 to line 1 and thus returned to the system.

A portion of the gases may be removed from the system through line 35 and valve 36. The gases may be enriched by the addition of hydrogen through line 37 and valve 38. The gasoline fraction or a fraction boiling substantially within the gasoline range is removed through line 39, valve 40 and pump 41, and is mixed with hydrogen-containing gas from separation step 27, entering through line 42 and valve 43. The mixture passes through line 44 and valve 45 to coil 46 which is disposed in heater 47. It is mixed with a suitable reforming catalyst from catalyst charger 48, passing through line 49, valve 50, pump 51 and valve 52. This catalyst may consist of a relatively inert support such as alumina, magnesia, bauxite, silica, diatomaceous earth, zinc oxide, titania and the like, having deposited thereon a promoting compound or compounds and particularly an oxide of a metal appearing in the left-hand column of groups IV, V and VI of the periodic table. Particularly suitable for this purpose are the oxides of chromium, molybdenum, vanadium, and tungsten. These catalytic agents are not necessarily equivalent in their action and the process is not intended to be limited to the particular catalyst described. The reaction mixture passes through line 53 and valve 54 to reactor 55, being maintained at a temperature within the range of approximately

900-1200° F. and pressures preferably atmospheric or slightly superatmospheric, of the order of 50-100 pounds per square inch, although somewhat higher pressures may also be used. The mixture passes through line 56 and valve 57 to fractionator 58. Gasoline and gas are removed through line 59 containing valve 60, condenser 61 and valve 62, being collected in receiver 63 from which gasoline is recovered through line 64 and valve 65. The gasoline may be subjected to such subsequent stabilization and additional treatment as may be necessary to produce a finished product.

The receiver gases pass through line 66 containing valve 67, pump 68 and valve 69 to line 26 and thence to desulfurizer 27. Material boiling above the gasoline range is removed through line 70 and valve 71. The spent catalyst may be recovered therefrom and reactivated by heating with an oxygen-containing gas whereby carbonaceous deposits are removed therefrom and catalytic activity is restored.

Returning to fractionator 16, a distillate fraction of the desulfurized charging stock which may boil within the kerosene, gas oil or wax distillate boiling range, is removed through line 72 containing valve 73, pump 74 and valve 75. This is mixed with the powdered cracking catalyst from catalyst charger 16 entering through line 77 containing valve 78, pump 79 and valve 80. The mixture enters coil 81 which is disposed in heater 82 and is heated under catalytic cracking conditions of temperature and pressure, usually within the range of 500-1200° F. and substantially atmospheric to 1000 pounds per square inch pressure. The temperatures ordinarily employed are within the range of approximately 800-1100° F. and pressures below approximately 100 pounds per square inch.

The reaction mixture passes through line 83 and valve 84 to chamber 85. Spent catalyst and residual oil may be withdrawn through line 86 and valve 87, the catalyst being recovered and subjected to reactivating treatment preferably in the presence of an oxygen-containing gas whereby the catalytic activity is restored. A vaporous portion of reactants pass through line 88 and valve 89 to fractionator 90. Gasoline and gas are removed through line 91, valve 92, condenser 93 and valve 94 to receiver 95 from which gasoline is removed through line 96 and valve 97 to suitable stabilizing equipment not shown. The receiver gases pass through line 98, valve 99, pump 100, valve 101 to line 26 and desulfurizing step 27. An intermediate fraction of insufficiently converted oil from fractionator 90 may be recycled through line 102, valve 103, pump 104 and valve 105 to line 72 and thus to coil 81. The higher boiling fraction may be withdrawn in part through line 106 and valve 107. A portion or all of the oil may be passed through line 108, valve 109, pump 110 and valve 111 to line 19 and thus supplied to coil 4 of the primary desulfurizing step.

The catalyst used in the catalytic cracking step may consist of a composite of precipitated silica having deposited thereon minor amounts of refractory oxides such as alumina and/or zirconia. In addition, certain other promoting oxides such as those of molybdenum, uranium, thorium, etc., may also be added. The composite is prepared by the separate or simultaneous precipitation of the components under such conditions that a powder of particle size approaching colloidal dimensions is produced. This powder is washed

under such conditions that alkali metal ions are removed substantially completely.

Another catalyst which may be used may be selected from naturally occurring earths which have been activated by treatment with acids or other chemicals.

The catalysts described are not necessarily exactly equivalent in their action nor are the operating conditions under which they may be used to the best advantage necessarily exactly the same.

This process has the advantage that it permits the production of high antiknock gasoline of desirable properties and containing substantially no sulfur. This is accomplished under conditions such that the losses in volume, antiknock properties and other desirable properties of the gasoline, resulting from treatment of cracked or reformed gasoline in the usual manner, are substantially eliminated. By this method of treatment it is possible to produce a substantially sulfur-free product. Both the catalytic cracking and reforming steps have a tendency to produce gasoline of low sulfur content, but the sulfur is not completely eliminated. By giving the charging stock a preliminary treatment whereby a major portion of the sulfur contained therein is removed, the relatively minor amounts of sulfur left in the charge to the reforming and cracking steps are readily taken care of in these processes and the result is a gasoline containing little or no sulfur. The importance of removing sulfur substantially completely has been recently emphasized, particularly in regard to the antiknock properties of the gasoline when tetraethyl lead is added thereto to improve the octane number. The process has the advantage that increased yields of gasoline per pass are obtainable from charging stock which has been treated in this manner due to the removal in the hydrogenating step of impurities which tend to decrease the catalytic activity of the catalysts used in the subsequent steps.

It should be borne in mind that the hydrogenating step is intended to be operated under conditions such that little or no destructive hydrogenation occurs; that is, there is little or no conversion of the higher boiling hydrocarbons into the gasoline range.

The following example is given to illustrate the usefulness and practicability of the process but should not be construed as limiting it to the exact conditions given therein.

A fraction of hydrocarbon oil obtained by the distillation of crude oil to remove a fraction boiling from approximately 200-760° F. was mixed with approximately 2% by weight of a catalyst comprising molybdenum oxide deposited on alumina. This mixture may be treated at 1000 pounds per square inch and 700° F. in the presence of a hydrogen-containing gas and then separated into gas, gasoline, intermediate boiling fraction and residue. The gas may be desulfurized as described by treatment with tripotassium phosphate and a portion thereof returned to process.

A portion of residual oil containing partially spent catalyst in suspension may also be recycled while the major portion of the catalyst and higher boiling oil is withdrawn from the system. The catalyst is recovered and separately regenerated. A naphtha fraction boiling up to approximately 425° F. may be mixed with a portion of the desulfurized gases and subjected to catalytic reforming in the presence of a powdered catalyst comprising a major portion of

activated alumina having deposited thereon a minor portion of an oxide of chromium. The temperatures employed are of the order of 575° F. at substantially atmospheric pressure. A reformed gasoline having an antiknock value of 80 may be recovered. The sulfur content of this material is less than 0.001%. Receiver gases are subjected to a desulfurizing treatment to remove hydrogen sulfide. A fraction including kerosene and gas oil from the original desulfurization step may be catalytically cracked in the presence of a silica-alumina powdered cracking catalyst at a temperature of 1000° F. and substantially atmospheric pressure. Gasoline having an antiknock value of 79 may be recovered. The gases are sent to the gas desulfurizing step. A portion of the insufficiently converted oil may be returned to the primary desulfurizing step. The gasoline from the cracking step may have a sulfur content of approximately that of the reformed gasoline. When using 3 cc. of tetraethyl lead per gallon of gasoline, the increase in octane number obtainable from gasoline of the present process is approximately two numbers greater than that obtainable when a naphtha is reformed and the kerosene-gas oil fraction is cracked without the preliminary treatment.

I claim as my invention:

1. A process for the conversion of hydrocarbon oil, which comprises subjecting said oil to desulfurizing conditions in the presence of a desulfurizing catalyst and hydrogen whereby to form hydrogen sulfide from sulfur compounds and form a substantially sulfur-free oil, separating from the products of desulfurization a fraction comprising normally gaseous products including hydrogen and hydrogen sulfide and a gasoline fraction, treating the first mentioned fraction to remove hydrogen sulfide, returning at least a portion of the substantially hydrogen sulfide free gases to the desulfurization step, combining another portion of the substantially hydrogen sulfide free gases with said gasoline fraction and subjecting the mixture to reforming conditions in the presence of a dehydrogenating catalyst, to reform the gasoline and to form additional hydrogen, separating a hydrogen fraction including said additional hydrogen from the reformed gasoline, recovering the latter, and combining said hydrogen fraction with the nor-

mally gaseous products prior to the hydrogen sulfide removal step.

2. The process of claim 1 further characterized in that desulfurizing and reforming are accomplished in the presence of a comminuted catalyst suspended in the charge to each step.

3. The process of claim 1 further characterized in that a relatively heavy oil is separated from the products of desulfurization and returned to the desulfurization step for further treatment.

4. A process for the conversion of hydrocarbon oil, which comprises subjecting said oil to desulfurizing conditions in the presence of a desulfurizing catalyst and hydrogen whereby to form hydrogen sulfide from sulfur compounds and form a substantially sulfur-free oil, separating from the products of desulfurization a fraction comprising normally gaseous products including hydrogen and hydrogen sulfide, a gasoline fraction, a gas oil fraction and a fraction heavier than gas oil, returning the last mentioned fraction to the desulfurizing step, treating the first mentioned fraction to remove hydrogen sulfide, returning a portion of the hydrogen sulfide free gases to the desulfurizing step, combining another portion of the substantially hydrogen sulfide free gases with said gasoline and subjecting the mixture to reforming conditions in the presence of a dehydrogenating catalyst to reform the gasoline and to form additional hydrogen, separating a hydrogen fraction including the additional hydrogen from the reformed gasoline, recovering the latter, and combining said

30 hydrogen fraction with the normally gaseous products prior to the hydrogen sulfide removal step, subjecting said gas oil fraction to cracking conditions in the presence of a cracking catalyst, fractionating conversion products of the last named step to form a reflux condensate and to separate a stream of fractionated vapors, returning at least a portion of said reflux condensate to the desulfurizing step, and recovering the fractionated vapors.

5. The process of claim 4 further characterized in that the conversion products from catalytic cracking are fractionated to separate a light reflux condensate and a heavier reflux condensate, the latter returned to the desulfurizing step and the former returned to the cracking step.

GUSTAV EGLOFF.
